CLAIM

The ornamental design for a display screen with transitional graphical user interface, as shown and described.

DESCRIPTION

FIG. 1 is a front view of a first image in sequence of a display screen with transitional graphical user interface; FIG. 2 is a front view of a second image in sequence of a display screen with transitional graphical user interface; FIG. 3 is a front view of a third image in sequence of a display screen with transitional graphical user interface; and, FIG. 4 is a front view of a fourth image in sequence of a display screen with transitional graphical user interface. The appearance of the transitional graphical user interfaces sequentially transitions between the images shown in FIG. 1-4. The process or period in which one image transitions to another image forms no part of the claimed design. The broken line in the Figure shows an electronic device that houses a display screen, and form no part of the claimed design.
